UNITED STATES PATENT OFFICE.

HARRY W. DENHARD, OF SAN FRANCISCO, CALIFORNIA, ASSIGNOR TO THE CUTLER-HAMMER MFG. CO., OF MILWAUKEE, WISCONSIN, A CORPORATION OF WISCONSIN.

ELECTRIC FLUID-HEATER.

1,219,265.

Specification of Letters Patent. Patented Mar. 13, 1917.

Application filed November 15, 1911, Serial No. 660,370. Renewed December 20, 1915. Serial No. 67,956.

To all whom it may concern:

Be it known that I, HARRY W. DENHARD, a citizen of the United States, residing at San Francisco, in the county of San Francisco and State of California, have invented new and useful Improvements in Electric Fluid-Heaters, of which the following is a full, clear, concise, and exact description, reference being had to the accompanying drawing, forming a part of this specification.

This invention relates to electric fluid heaters and regulators therefor. It is especially adapted for electric heaters of the type wherein the fluid forms part of the circuit and is heated by the passage of the current through the same.

One of the objects of the invention is to provide an improved electric fluid heater and a regulator therefor.

Another object is to provide a regulator which will render the heater adapted to heat liquids of different specific resistance to any desired temperature.

Another object is to provide a compact regulator which will occupy little space in the heater and which at the same time will be readily accessible for adjustment.

Other objects and advantages of my invention will hereinafter appear.

In the accompanying drawings I have shown one form which my invention may assume in practice. My invention is not, however, limited to this form.

In the views of these drawings:

Figure 1 shows a central longitudinal section through a heater.

Fig. 2 shows a top plan view of the same.

Fig. 3 shows a side elevation of one of the tubes used in this form of regulator.

Fig. 4 shows a side elevation of another tube used in this form of regulator.

The fluid heater is provided with carbon electrodes 1 inclosed in a tubular metallic receptacle or casing 2. Two sets of electrodes are provided, one positive and the other negative. The electrodes are suitably spaced apart from each other and from the casing and they have their ends received by suitable conducting blocks 3 and insulating blocks 4. Terminal connections for the electrodes are provided at the upper ends of the

casing. The bottom of the casing has an inlet opening 5 therein and adjacent said opening, but separated therefrom by a diaphragm, is an outlet opening 6.

55

A chamber is provided in one side 9 of the casing in which tubes 7 and 8 are located. These tubes communicate with the outlet opening and are arranged to form an outlet passage from the exterior of the receptacle 60 to the outlet opening. The tubes are preferably long and narrow and extend longitudinally throughout the entire length of the receptacle. The tube 8 is arranged to rotate within the tube 7 as will hereinafter be described. The tube 7 is fixed in the casing. It has a longitudinal slot 11 therein which communicates with the interior of the receptacle. The tube 8 is provided with a spirally arranged series of openings 12 70 which coöperate with the slot 11 in tube 7 as the tube 8 is rotated. It will be understood that a spirally arranged slot may be used if desired.

The tube 8 is also provided with a relatively large opening 13 which is adapted to coöperate with the corresponding opening 14 in the tube 7, so that when the receptacle is practically filled with fluid, a relatively large passage is provided the size of which 80 may be regulated to control the flow.

The tube 8 is rotated by means of a threaded stud 15 which is carried by the top 10 of the casing and arranged to be rotated from the exterior thereof.

85

When the regulator is assembled, as shown in Fig. 1, the slot 11 in tube 7 is arranged to communicate directly with the interior of the casing 2 and one or more of the perforations 12 or a portion of the slot, if this is 90 used, is opposite the slot 11. Thus an opening is formed through the tubes, which permits the water in the casing to pass out and down to the outlet 6. The height of this opening determines the height which the 95 water in the casing may reach. By suitably adjusting the inner tube 8 within the tube 7, so that any predetermined one or more of its openings may coincide with the slot in the outer tube 7, this water level may be 100 varied as desired, and the heater adapted to heat liquids of different resistance, since it is

a well known fact that the resistance developed is inversely proportional to the cross section of the conductor. Therefore, by varying the amount of water through which 5 the current passes, the heater may be so adjusted as to operate at its maximum efficiency upon liquids of widely different resistances and to heat the water to any desired degree.

10 In the construction in Fig. 1, the carbon-electrodes 1 are arranged in a plurality of concentric series so that the fluid in the casting acts to complete the circuit through the electrodes. One or more rods 16 are so arranged that they serve not only to support the electrodes but to provide terminal connections at one end of the same. In Fig. 1 the central rod is provided with a threaded upper end and a threaded lower end. The 20 threaded lower end carries the lower conducting plate 3, which in turn carries the insulating block or plate 4 in which certain of the electrodes are seated. The upper threaded end of the rod extends through the upper 25 insulating plate 4 and the upper conducting plate 3 to the outside of the top plate 10 and is insulated from the conducting plate 3 by a suitable insulating sleeve 17. Suitable means 18 for connecting the end of a conductor are carried upon the threaded end which extends beyond the cover 10. Obviously another rod may be connected in a similar manner at the side of the heater so that the terminal connections for the heater 30 may be at the top of the same. If desired, the terminal connections may be inclosed in a suitable cap or cover 19 of any desired shape. A very sturdy structure is thus provided wherein the electrodes are prevented 35 from jarring and breaking when the heater is roughly used, and in which the terminal connections may be conveniently made.

It will thus be seen that a fluid heater has been provided in which the amount of fluid 40 acting as a conductor between the electrodes may be readily varied so that the heater will operate efficiently to heat fluids of any specific resistance to any desired temperature. The fluid may be continuously passed 45 through the heater and the amount of heat imparted to the fluid readily controlled. The regulator for the heater is inclosed within the heater casing and it occupies a small amount of space so that the apparatus 50 as a whole may be made very compact and neat. The structure is rugged and may therefore be handled roughly without damaging the parts or getting them out of adjustment. The terminal connections are 55 conveniently located and neatly covered so as to present an unobtrusive appearance and at the same time are readily accessible. The structure thus constitutes a neat, compact and convenient means for heating fluids of 60 any kind. This means is constructed so that 65

it may be quickly adjusted to secure a maximum efficiency under a wide variation of conditions.

It should, of course, be understood that the structure shown is for purposes of illustration only and that other structures may be devised which embody the invention and which come within the spirit and scope of the appended claims. 70

What I claim as new and desire to secure 75 by Letters Patent of the United States is as follows:

1. An electric fluid heater comprising a receptacle provided with an inlet and an outlet opening, electric heating means within 80 said receptacle, and means within said receptacle communicating with the outlet opening and rotatably adjustable from the outside of the receptacle for regulating the height of the fluid in the receptacle whereby 85 the heater may be readily adjusted to operate at maximum efficiency for fluids of different specific resistance.

2. An electric fluid heater comprising a tubular receptacle having an inlet opening 90 near the bottom thereof, a plurality of electrodes longitudinally disposed within said receptacle and adapted to be electrically connected by the fluid in the receptacle, and means within the receptacle communicating 95 with the outlet opening therein, said means being longitudinally disposed within the receptacle and rotatably adjustable from the exterior thereof to regulate the height of the fluid in the receptacle, whereby the heater 100 may be adjusted to operate at maximum efficiency for fluids of different specific resistance.

3. An electric fluid heater comprising a receptacle provided with an inlet and an 105 outlet opening, a plurality of positive and negative electrodes within said receptacle and a pair of tubes, one within the other, in 110 said receptacle, said tubes communicating with the outlet opening and each having 115 openings therein adapted to coöperate to form a passage communicating with the interior of the receptacle, the one of said tubes being adjustable relative to the other so that the height of said passage above the 115 bottom of the receptacle may be regulated.

4. An electric fluid heater comprising a tubular receptacle having an inlet opening near the bottom thereof, a plurality of positive and negative electrodes longitudinally 120 disposed in said receptacle, a pair of tubes, one within the other, longitudinally disposed in the receptacle and communicating with an outlet opening therein, said tubes having coöperating openings therein adapt- 125 ed to form a passage communicating with the interior of the receptacle, one of said tubes being adjustable relative to the other from the exterior of the receptacle to vary the location of the passage to regulate the height 130

of the fluid flowing through said receptacle whereby the heater may be adjusted to operate at maximum efficiency.

5. An electric fluid heater comprising a tubular receptacle having an inlet opening near the bottom thereof, a plurality of positive and negative electrodes longitudinally disposed within said receptacle, a tube longitudinally disposed within said receptacle 10 and communicating with an outlet opening therein, said tube having a longitudinal slot therein, a second tube within the first having a series of spirally arranged openings therein adapted to successively register with the slot in the first tube, means operative 15 from the exterior of the receptacle for adjusting the position of the second tube relative to the first whereby the heater may be regulated to operate at maximum efficiency 20 for fluids of different specific resistance.

6. An electric fluid heater comprising a tubular receptacle having an inlet opening, a removable cover for said receptacle, a plurality of positive and negative electrodes 25 disposed longitudinally in said receptacle and carried by said cover, means adjustable from the exterior of the receptacle and disposed along one side of the interior thereof and communicating with an outlet opening 30 therein for regulating the height of the fluid flowing through said heater whereby the heater may be adjusted to operate at maximum efficiency.

7. An electric fluid heater comprising a tubular casing having an inlet opening near the bottom thereof, electric heating means within the casing and means disposed along one side of the casing and rotatably adjustable from the exterior thereof for regulating the height of the fluid in said receptacle.

8. An electric heater for heating a flowing fluid comprising a closed receptacle having an inlet and an outlet opening, electric heating means within the receptacle and means communicating with the outlet opening and rotatably adjustable from the exterior of the receptacle for regulating the height of the fluid in the receptacle whereby the heater 50 may be adjusted to operate at maximum efficiency.

9. A heater for heating a flowing fluid comprising a receptacle provided with an inlet and an outlet opening, electric heating means 55 within said receptacle, and rotatable means within said receptacle adjustable from the exterior thereof for regulating the height of the fluid in the heater whereby the heater may be adjusted to operate at maximum efficiency.

10. A heater for heating a flowing fluid comprising a receptacle provided with an inlet and an outlet opening, a cover for said receptacle, electric heating means within 65 said receptacle supported by said cover and

rotatable means within the receptacle adjustable from the exterior thereof for regulating the height of fluid in the receptacle whereby the heater may be adjusted to operate at maximum efficiency.

11. A heater for heating a flowing fluid comprising a receptacle provided with an inlet and an outlet opening, a cover for said receptacle, a plurality of positive and negative electrodes disposed within said receptacle and supported by said cover and rotatable means adjustable through said cover for regulating the height of fluid in the receptacle whereby the heater may be adjusted to operate at maximum efficiency.

12. A heater for heating a flowing fluid comprising a tubular receptacle having an inlet and an outlet opening, a cover for said receptacle supporting electric heating means longitudinally disposed within the receptacle, and rotatable means longitudinally disposed within the receptacle and adjustable from the exterior thereof to regulate the height of fluid in the receptacle whereby a neat, compact structure capable of being adjusted to operate at maximum efficiency is provided.

13. A heater for heating a flowing fluid comprising a receptacle provided with an inlet and an outlet opening, a cover for said receptacle supporting a plurality of positive and negative electrodes disposed within the receptacle, one of said electrodes acting as a terminal rod and as a supporting means for a structure supporting the lower ends of the electrodes, and means within said receptacle adjustable from the exterior thereof for regulating the height of fluid in the receptacle whereby the heater may be adjusted to operate at maximum efficiency.

14. A heater for heating a flowing fluid comprising a tubular receptacle having an outlet and an inlet opening in the bottom thereof, a cover for the top of the receptacle supporting a plurality of positive and negative electrodes longitudinally disposed within the receptacle and a pair of tubes, one within the other and one rotatably adjustable relative to the other by means extending through the cover to regulate the height 115 of fluid in the receptacle.

15. A heater for heating a flowing fluid comprising a receptacle having an inlet and an outlet opening, a cover for said receptacle, electric heating means disposed within the 120 receptacle and supported from the cover thereof, and means within the receptacle adjustable by means extending through the cover for regulating the height of fluid in the receptacle.

16. A heater for heating a flowing fluid comprising a tubular receptacle having an inlet and an outlet opening, electric heating means longitudinally disposed within said receptacle, a chamber on one side of said 125

receptacle, means within the chamber communicating with the outlet opening in the bottom of the receptacle and adjustable from the exterior and top of the receptacle to regulate the height of fluid therein.

17. A heater for heating a flowing fluid comprising a receptacle having an inlet and an outlet opening, electric heating means within the receptacle and means within the receptacle adjustable from the exterior thereof for regulating the height of fluid flowing through the receptacle, said means being also adjustable to regulate the rate of flow through the receptacle when the heater is substantially filled.
18. A fluid heater comprising a recep-

tacle having an inlet and an outlet opening, electric heating means within the receptacle and means within the receptacle rotatably adjustable from the exterior thereof for regulating the height of fluid in the receptacle, said means being also adjustable to regulate the rate of flow through the receptacle when the heater is operating at substantially its full capacity. 25

In witness whereof, I have hereunto subscribed my name in the presence of two witnesses.

HARRY W. DENHARD.
